[57] CLAIM

The ornamental design for a combined powerboard and reel, as shown and described.

DESCRIPTION

FIG. 1 is a top, front perspective view of the combined powerboard and reel showing my new design;
FIG. 2 is a bottom rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and
FIG. 8 is a bottom plan view thereof.

The electric cord is shown broken away in FIGS. 1 and 2 to depict indeterminate length and shown in fragment in FIGS. 3-8 for ease of illustration only.
